CUT-MEASURING AND STOPPING MEANS FOR LOOMS.

No. 907,962.

Specification of Letters Patent.

Patented Dec. 29, 1908.

Application filed January 20, 1908. Serial No. 411,580.

To all whom it may concern:

Be it known that I, HOWARD W. BRACKEN, a citizen of the United States, and resident of Hopedale, county of Worcester, State of Massachusetts, have invented an Improvement in Cut-Measuring and Stopping Means for Looms, of which the following description, in connection with the accompanying drawing, is a specification, like letters on the drawing representing like parts.

This invention has for its object the production of novel means for measuring a predetermined length or "cut" of cloth when woven on a loom and for effecting the stoppage of the loom automatically when the "cut" has been woven.

In cloth weaving the "cut" has a predetermined length, differing with the character of the goods and with different mills, but ordinarily for a given weave-shed the length of the cut is fixed, and it is customary for the weaver to mark the "cut" in some suitable manner. Sometimes this is done by weaving in so called "headers" at the completion 25 of each cut, as by weaving two or more picks of filling differing in color or character from the filling in the body of the cut, and it is highly desirable that all the cuts woven on a given loom, or group of looms, shall be of the same length. This uniformity in the length of the cut is secured by the present invention, and the construction of the mechanism is such that an improper shortening of the cut by the weaver is guarded against, while 35 the automatic stoppage of the loom at the completion of a cut enables one weaver to take charge of a number of looms and give general attention thereto, knowing that no loom can weave more than the desired cut 40 without being stopped automatically.

I have provided means for readily adjusting the measuring mechanism by an authorized person, so that the desired length of cut will be woven before the loom is stopped, and 45 the mechanism is so arranged that after a cut has been started it is practically impossible for the weaver to tamper with the apparatus without speedy detection, particularly as weavers are forbidden to have in their possession any tool which would permit of their changing any mechanism on the loom.

The various novel features of my invention will be fully described in the subjoined specification and particularly pointed out in 55 the following claims.

Figure 1 is a transverse section of a sufficient portion of a loom, with one embodiment of my present invention applied thereto, the nearer loom-side being partly shown, the section in general being taken on the line 1—1, Fig. 2, looking toward the right; Fig. 2 is a front elevation of the mechanism illustrated in Fig. 1 which is located at or near the right-hand side of the loom; Fig. 3 is an enlarged detail in top plan view of a 60 part of the instrumentality for effecting loom stoppage, taken below the line 3—3, Fig. 2; Fig. 4 is a partial section on the line 4—4, Fig. 3; Fig. 5 is a plan view and section, taken on the line 5—5, Fig. 2, of the tripping 65 member governed by the measuring means; Fig. 6 is a similar view of the tripping device but showing it in the act of being opened or disengaged from the measuring means, in readiness to be moved manually to 70 starting position preparatory to beginning a cut of cloth; Fig. 7 is a detail of one part of the device for effecting loom stoppage, to be referred to.

The breast-beam 1, shipper 2, the cloth-roll shaft 3 on which the cloth is wound as taken up, the take-up roll 4, the cloth-guide 5 back of the take-up roll, the cloth-support 6, and supplementary support 7, see Fig. 1, and the mechanism for operating the take-up roll, may be of well known construction, such for instance as shown in United States Patent No. 789816, granted to Nutting May 16, 1905.

In the present embodiment of my invention I have operated the cloth-measuring mechanism by or through a convenient part of the take-up, to wit, the take-up roll, because by so doing a correct measurement of the actual cloth passing over such roll is registered but it will be obvious that there are other moving parts of the loom which could be used to actuate the cloth-measuring mechanism. That is, the motion of the lay could be utilized, for there is a definite movement of the lay for every pick put into the cloth.

While the take-up motion is most convenient for the purpose, and I prefer to use it any motion which gives a record of or corresponds to the number of picks put into the cloth, or gives the actual length of the cloth may be utilized instead of the take-up motion.

At one end of the take-up roll I attach a 112

gear 8 which meshes with a pinion 9 which in turn drives a pinion 10 fast on a horizontal shaft 11, see Fig. 2, carrying at its outer end a bevel-gear 12, the pinion 9 being carried by an adjustable gear-plate 13, held in adjusted position on the cloth-roll stand 14 by bolt 15, so that pinions of different diameter may be used.

The cloth-roll stand 14 forms a part of the take-up structure and is of well known construction, except that herein I have shown it provided with a sleeve-bearing 16^x for the shaft 11, the bevel-gear 12 on said shaft meshing with a similar gear 16, Fig. 2, fast on the upper end of a vertical shaft 17, screw threaded at 18 for the greater part of its length, as shown in Figs. 1 and 2, said shaft having an upper bearing in a shelf-like bracket 19 bolted to the loom-side A^x, and a lower step-bearing 20 being formed in a second bracket 21 bolted to the loom-side and to the cross-girt A², Fig. 2.

A guide-rod 22 parallel to the threaded shaft 17 is held at its upper and lower ends in the brackets 19 and 21, behind but a short distance from said shaft, the lower end of said guide-rod being held fast by a set-screw 23, Fig. 1.

From the foregoing it will be manifest that the threaded shaft 17 is rotated by or through the take-up roll, the transmitting gearing being so arranged and proportioned that for each complete revolution of the take-up roll the shaft will be given a predetermined angular or rotative movement, which is made operative to throw into action a loom-stopping instrumentality when a predetermined number of revolutions of the take-up roll have measured a certain number of yards of cloth, *i. e.* a "cut," as will be described.

A tripping device is mounted slidably upon the guide-rod 22 and normally operatively engages the threaded part 18 of the shaft 17, to be moved upward by rotation thereof, said device being herein shown as comprising two pivotally connected members 24, 25, the hub 24^x of the former being bifurcated to embrace the hub 25^x of the latter, both hubs embracing the guide-rod 22, Figs. 5 and 6. The members of the tripping device are thus adapted to be closed together, as in Fig. 5, to embrace the threaded part 18 of the screw-shaft, by means of threaded seats 26, 27, or they can be swung out to be disengaged from the shaft, as in Fig. 6.

The free ends of the members are slotted, the slot in the member 24 receiving the pivotally connected end of a threaded locking rod 28 provided with a nut 29, said rod entering the slot 30 in the member 25, as in Fig. 5, so that by setting up the nut 29 the tripping device is locked upon the screw-shaft in operative engagement therewith, see Fig. 5. The member 24 is provided with

a lateral lug 31, and the member 25 has a toe 32 extended therefrom near its hub 25^x, for purposes to be described. When the members 24 and 25 are locked together their opposed faces abut, so that tightening of the nut 29 cannot clamp the tripping device upon the screw shaft.

A collar 33 is adjustably held by a set-nut 34, Fig. 1, on the guide-rod 22, serving as a stop to limit the downward movement of the tripping device after a cut has been completed, the tripping device being gradually moved upward by rotation of the screw-shaft 17 as the weaving of the cut progresses.

An upright bar 35 is bolted to the brackets 19 and 21 at one side of the screw-shaft, and on this bar I mount an adjustable gage, herein shown as an elongated plate 36 projecting beyond the bar toward the screw-shaft and having a notch 37 near its lower end as clearly shown in Fig. 2.

The gage-plate is longitudinally slotted at 38, see dotted lines, Fig. 2, to receive the shanks of setting screws 39 extended into the bar 35, so that the gage-plate may be shifted longitudinally to raise or lower the notch 37.

When the tripping device is in operative engagement with the screw-shaft 17, as in Figs. 1, 2 and 5, the toe 32 extends over and is close to the projecting edge of the gage-plate 36, so that even if the nut 29 is loosened the member 25 cannot be swung around the guide-rod 22 and disengaged from the screw-thread 18, except when the toe 32 is opposite the notch 37. At such time the toe will swing through the notch and permits complete opening of the tripping device, it being understood that when said device is completely open the toe 32 will have been moved still further to the left, viewing Fig. 6, beyond the edge of the gage-plate. Thereupon the tripping device can be moved freely longitudinally of the guide-rod 22.

The position of the notch 37 determines the starting point of the travel of the tripping device, for when the toe 32 is opposite the notch the members 24 and 25 of the tripping device can then be closed and locked around the screw-shaft, and as the stopping point of the travel of said tripping device is always the same the movement of the gage-plate up or down will shorten or lengthen, respectively, the length of such travel. An auxiliary plate 40 is adjustably secured to the bar 35 above the upper end of the gage-plate 36, to partly fill in the space between the latter and the bracket 19. After the tripping device has been locked as described and the upward travel begun it cannot be unlocked so long as the toe 32 extends over the edge of the gage-plate, hence the travel of the tripping device must be, at the minimum, to the top of said plate 36. As a matter of fact while the weaver could unlock the

the tripping device at such point, and return it to starting position the length of the cut would be so much less than the proper length that detection would be made easy.

- 5 The auxiliary plate 40 is a safe-guard, as it makes it incumbent on a weaver to watch the loom closely if there be any intention to shorten the cut, so that when the toe 32 arrives opposite the space between the plates 10 36 and 40 the tripping device can be unlocked. When running a number of looms, however, a weaver could not give this attention to any particular loom and the chances of improper manipulation are minimized. 15 When the tripping device arrives at the upper end of its travel the lug 31 acts upon a detent 41, lifting it from the position shown in Fig. 4 and out of engagement with a shoulder 42 on a latch 43 releasing the latter. 20 This latch is preferably a squared portion of a rod 44 slidable in a bearing 45 on the bracket 19, the latch traveling in a seat 46 on the bracket and having an attached handle 47 slidable in a bearing 48, the bracket being 25 cut out at 49, see Fig. 3, adjacent the seat 46, to loosely receive the detent. A spring 50 normally acts to move the rod to the right, Figs. 3 and 4, whenever the detent 41 is lifted to release the shoulder 42, such 30 spring-actuated movement effecting the actuation of a loom stopping instrumentality, as will be explained.

The opening in the detent, through which the latch passes when released, is sufficiently 35 large for the purpose, as shown in Fig. 4, and when the weaver is about to start the loom after it has been stopped through the action of the cut measuring means he pushes in the handle 47, against the spring 50, the 40 detent 41 dropping into operative position in front of the shoulder 42 on the latch, as will be manifest, but before doing this the weaver has unlocked the tripping device and restored it to starting position.

45 In Figs. 1 and 2 the latch is supposed to be in the position shown in Figs. 3 and 4, and the tripping device has been moved, by rotation of the screw-shaft 17, to a point above the notch 37, indicating that the weaving of 50 a cut has begun, and the rise of the tripping device will continue until the lug 31 lifts the detent and releases the latch 43.

The adjustment of the gage-plate to fix the starting point for the tripping device is not 55 made by the weaver, but by the loom-fixer or overseer, and there is little likelihood of an attempt being made by the weaver to change the adjustment, as tampering with the gage-plate or the setting screws 39 therefor would 60 be quickly noticed by those in authority.

Herein I have arranged the stoppage of the loom, at the completion of a cut, to be effected by or through the warp-stop motion as an easy and convenient way of so doing, 65 and in Fig. 1 a sufficient portion of a stop-

motion is shown substantially as illustrated in United States Patent No. 673824 granted to Stimpson May 7, 1901.

A rock-shaft F has an attached, double-throw feeler f adapted to engage and be arrested by a released detector d in either of the two banks or series shown, vibratory motion being imparted to the feeler by or through the links h², h³ from the feeler cam C on the cam-shaft C^X of the loom. When the feeler f is arrested the link M is moved in the direction of the arrow by co-operation of one of the tappets t or t' with a usual bunter, and such movement of the link turns a rock-shaft m²² and thereby moves the knock-off arm m²³ to release the shipper 2, and stop the loom.

To make the warp stop-motion effective to stop the loom when a cut is completed I mount loosely on the rock-shaft F an up-turned finger 51 having its tip bent at 52 into the path of one of the arms f^X supporting the feeler. Said finger has a depending extension 53 connected by a link 54 with the latch rod 44, see Fig. 1.

When the latch 43 is held by the detent, as in Figs. 3 and 4, the extension 53 is positioned to throw the finger forward, with its tip 52 out of the way of the arm f^X, but when the latch is released the spring 50 moves the rod 44 and link 54 to the right, viewing Fig. 1, and swinging the extension 53 forward, as shown in Fig. 7. This places the finger tip 52 in position to stop the feeler just as if a detector in the front bank had arrested it, and thereupon the stopping instrumentality of the loom is caused to operate.

The weaver can tell when the cut measuring means has caused loom stoppage by noting the position of the enlarged end of the handle 47, for if a cut has been completed and the loom is stopped on account of such completion the handle will be projected to abnormal position.

It will be obvious that the cut measuring means, comprising the screw-shaft and the tripping device actuated thereby, is positively actuated by the take-up mechanism and under its control during the formation of a cut.

The loom cannot be started unless the latch is in normal, locked position, as will be obvious from the foregoing description, and the locking of the latch properly positions the detent for release by the tripping device when a cut has been completed.

Having fully described my invention, what I claim as new and desire to secure by Letters Patent is:—

1. In a loom, in combination, cloth-measuring means, including a spirally-threaded member, and a tripping device co-operating normally therewith and moved longitudinally of said member by rotation thereof, take-up mechanism operatively con- 125

4
nected with said member to rotate it, means positively actuated by the tripping device at one end of its travel to effect the operation of a loom-stopping instrumentality, and 5 adjustable means to determine the other or starting end of such travel of the tripping device and prevent the starting thereof from any different point.

2. In a loom, in combination, take-up 10 mechanism, cloth-measuring means, including a spirally-threaded member rotated by or through said mechanism, and a tripping device normally co-operating with and moved by said member, a fixed guide-rod parallel 15 to the latter and on which the tripping device slides longitudinally, manually adjustable means to determine the extent of travel of the tripping device, to correspond to a predetermined length of cloth taken up, 20 and means actuated by direct engagement with the tripping device to effect the action of a loom-stopping instrumentality when said device has traveled a predetermined distance.

25 3. In a loom, in combination, cloth-measuring means, including a spirally-threaded member, and a tripping device normally co-operating therewith to be moved longitudinally of said member by its rotation, take-up 30 mechanism, including a take-up roll operatively connected with the threaded member to rotate the same, means, including a latch and a detent to normally lock the latch, to effect the operation of a loom stopping 35 instrumentality when the tripping device moves the detent to release the latch, the detent being located at one end of the path of movement of said device, and a manually adjustable gage to determine the 40 point at which the travel of the tripping device shall begin.

4. In a loom, take-up mechanism, including a take-up roll, a spirally-threaded measuring shaft, connections between it and the take-up 45 roll to effect positive rotation of said shaft, a tripping device comprising separable members to operatively embrace the shaft and be moved longitudinally thereof, means to lock the members together, and a toe extended 50 laterally from one of the members, a fixed guide-rod on which said tripping device is slidable longitudinally, and an adjustable gage-plate extended along the path of movement of the toe and having a notch in its 55 edge, said plate permitting relative movement of the members of the tripping device when the toe is opposite the notch, the latter determining the starting point for the tripping device when moved by the measuring 60 shaft, combined with means actuated by the said tripping device at the completion of its movement to effect the operation of a loom-stopping instrumentality.

5. In a loom, take-up mechanism, cloth- 65 measuring means actuated thereby, includ-

ing a rotating screw-shaft and a tripping device having relatively movable members to operatively engage and be moved by said shaft in the direction of its length, said device having a toe extended therefrom, means 70 to act in conjunction with the toe and prevent relative opening movement of the tripping device members to disengage them from the shaft, except at predetermined points, and a stopping instrumentality the 75 operation whereof is effected by the tripping device when it reaches the end of its movement due to rotation of the screw-shaft.

6. In a loom, cloth-measuring means including a rotating member, a traveling member moved thereby in parallelism with the axis of the rotating member and manually brought into or out of engagement with the rotating member, means to effect loom stoppage by or through direct engagement with 80 and positive actuation by the traveling member when it reaches the end of its travel, adjustable means to determine the starting point of such travel and to thereafter prevent disengagement of the rotating and traveling 85 member through the greater part of the movement of the latter, and take-up mechanism positively connected with and to actuate the rotating member of the measuring means. 95

7. In a loom, take-up mechanism, a stopping instrumentality adapted to be operated by or through a warp fault, means, including a spring-actuated latch, to effect the operation of the stopping instrumentality independently of a warp-fault, a detent to retain the latch in inoperative position, and means operated by the take-up mechanism to act upon the detent and release the latch when a predetermined length of cloth has been taken 105 up, said latter means including a member movable in a straight, elongated and fixed path, and manually governed means to vary the length of such path.

8. In a loom, a stopping instrumentality 110 adapted to be actuated by or through a change in the normal operation of the loom, take-up mechanism, means positively connected therewith and actuated thereby to measure a predetermined length of cloth 115 taken up, said means including a tripping device, means, including a spring-actuated member and a detent therefor, to effect independent operation of the stopping instrumentality when the tripping device is moved 120 into engagement with the detent, and a manually governed and normally stationary gage to vary the effective path of movement of said tripping device.

9. In a loom, in combination, take-up 125 mechanism, a screw-shaft operatively connected with and rotated by said mechanism, a member adapted to engage the screw-shaft to be operatively moved thereby in a longitudinal path by rotation of the shaft and to 130

be manually disengaged from said shaft and moved to starting position, stationary means to prevent such disengagement during the major part of the operative movement of said member, a loom stopping instrumentality, and means to effect the operation thereof by or through coöperation with the said member when it has completed its operative movement.

10 10. In a loom, in combination, cloth-measuring means, including a spirally-threaded member, and a tripping device coöoperating normally therewith and moved longitudinally of said member by rotation thereof, a definitely moving part of the loom operatively connected with said member to rotate it, means actuated positively by the tripping device at one end of its travel to effect the operation of a loom-stopping instrumentality, and adjustable means to determine the other or starting end of such travel of the tripping device and prevent the starting thereof at any other point.

11 11. In a loom, cloth-measuring means including a rotating member, a traveling member moved thereby in parallelism with its axis of rotation and manually brought into and out of engagement with the rotating member, means to effect loom stoppage by or through coöperation with the traveling member when it reaches the end of its travel, adjustable means to determine the starting point of such travel and to thereafter prevent disengagement of the rotating and traveling member through the greater part of the movement of the latter, and means connected with and to actuate the rotating member of the measuring means.

12 12. In a loom, a stopping instrumentality adapted to be actuated by or through a change in the normal operation of the loom, mechanism having a predetermined movement for each pick, means actuated thereby to measure a predetermined length of cloth taken up, said means including a tripping device, means, including a spring-actuated

member and a detent therefor, to effect independent operation of the stopping instrumentality when the tripping device is moved into engagement with the detent, and a manually governed gage to vary the effective path of movement of said tripping device.

13. In a loom, in combination, a screw-shaft, a moving part of the loom positively and operatively connected therewith to rotate it a definite amount on each pick, a member adapted to engage the screw-shaft to be operatively moved thereby in a longitudinal path by rotation of the shaft and to be manually disengaged from said shaft and moved to starting position, means to prevent such disengagement during the major part of the operative movement of said member, a loom stopping instrumentality, and means to effect the operation thereof by or through coöperation with and positive movement by the said member when it has completed its operative movement.

14. In a loom, in combination, cloth-measuring means, including a spirally-threaded member, and a tripping device normally coöoperating therewith to be moved longitudinally of said member by its rotation, mechanism operatively connected with and to rotate the threaded member a definite amount on each pick, means, including a latch and a detent to normally lock the latch, to effect the operation of a loom stopping instrumentality when the tripping device moves the detent to release the latch, the detent being located at one end of the path of movement of said device, and a manually adjustable gage to determine the point at which the travel of the tripping device shall begin.

In testimony whereof, I have signed my name to this specification, in the presence of two subscribing witnesses.

HOWARD W. BRACKEN.
